BENJAMIN BABBITT, OF NEW YORK, N. Y.

Letters Patent No. 77,240, dated April 28, 1868.

IMPROVED QUARTZ-CRUSHER.

The Schedule referred to in these Letters Patent and making part of the same.

TO ALL WHOM IT MAY CONCERN:

Be it known that I, BENJAMIN BABBITT, of the city, county, and State of New York, have invented a new and improved Quartz-Crusher and Pulverizer; and I do hereby declare that the following is a full, clear, and exact description thereof, which will enable others skilled in the art to make and use the same, reference being had to the accompanying drawings forming a part of this specification.

This invention relates to a new and improved apparatus or device for crushing and pulverizing quartz, and it consists of a series of crushers, arranged on the toggle principle, and provided at one end with elastic or yielding bearings, whereby the crushers are allowed to yield or give in case of coming in contact with any foreign substance, such as spikes or other metal articles, and the crushers prevented from being injured or broken thereby.

The invention further consists in a novel construction of pressure-rollers for pulverizing the crushed quartz, whereby the rollers are allowed to yield or give to admit of any hard foreign substance escaping between them without injuring the rollers or subjecting the same to any undue strain.

In the accompanying sheet of drawings—

Figure 1 is a side sectional view of my invention, taken in the line *z z*, fig. 2.

Figure 2, a plan or top view of the same.

Figure 3, a detached vertical section of the bearing of one of the pressure-rollers, taken in the line *yy*, fig. 2.

Figure 4, a detached horizontal section of one of the pressure-rollers.

Similar letters of reference indicate corresponding parts.

A represents the frame of the machine, which may be constructed in any proper manner to support the working parts.

On the top of this frame A there is secured a box, B, which is divided into three compartments by partition-plates, *a*, and in each of these compartments a toggle, C, is placed. These toggles, at one end, are connected by pivots *b* to shoes C', the lower ends of which are all fitted loosely on a shaft, D, the latter passing transversely through one end of the box B. The opposite ends of the toggles are connected by pivots, *c*, to slides, E, between which and the end of the box B, springs F, of India rubber or other suitable material, are placed, and within each compartment there are secured two eccentrics, *d d*, by turning or adjusting which the slides may be pressed more or less back, and the play or movement of the slides E regulated as occasion may require.

In fig. 2 only one slide, E, is shown, but in practice it is designed to have all the toggles attached to them, a slide to each toggle.

The shoes C' are operated by raising the toggles, which is done by means of cams G on a shaft H, the latter being turned by gears *e f* from the shaft *g* of one of the pressure-rollers hereinafter described.

I is a chute, which leads from the shoes O' down to the pressure-rollers J J', and conducts the cracked quartz from the shoes to said rollers. The quartz is cracked between the shoes and the end of the box B, the cracking being effected when the central portions of the toggles are forced upward under the action of the cams G. As the toggles are relieved from the prominent portions of the cams, they drop by their own gravity, and are raised again by the prominent portions of the cams as they again come around. The shoes are prevented from being injured by any hard foreign substance passing down between them and the end of box B, by the yielding of the slides E, the springs F admitting of this. The pressure of the shoes C' against the end of box B may be regulated as desired by adjusting the eccentrics *d d*.

The pressure-roller J may be of ordinary construction, and the bearing, *h*, of its shaft, *i*, are not fixed, but allowed to slide a certain distance, and they bear against rubber springs, *j*, which are interposed between the bearings and plates *k*, as shown clearly in fig. 2.

The bearings *h'* of the other roller J' are similarly arranged, *j'* representing the springs and *k'* the plates, (see fig. 3.) The position of the plates *k k'* of both rollers may be adjusted by set-screws *o*.

The roller J' is of practical construction. Its shaft, *g*, has two collars, *q q*, firmly secured upon it, and India-rubber heads, *r r*, are placed upon the shaft, and bear against the collars *q q*, and loose collars, *o o*, are

placed upon the shaft g , at the opposite sides of the heads, the collars o being pressed up against the rubber heads r by means of nuts t .

By this arrangement, the India-rubber heads r may be expanded to fit tightly within a hollow cylinder, u , which forms the periphery of the roller J' . This will be fully understood by referring to fig. 4. The rubber heads, it will be seen, admit of the cylinder u , which is the periphery of the roller J' , yielding or giving in case of any hard foreign substance, such, for instance, as pieces of iron, passing between them.

This yielding of the roller J' , in connection with the yielding of the bearings in which their shafts are fitted, will effectually prevent the rollers or any of their parts being broken, strained, or injured by the passage of any hard foreign substance between them.

Motion is communicated to the machine from the driving-shaft K to the shaft of roller J by means of a worm-wheel and screw $a \times b \times$, (see fig. 2.)

The rollers $J J'$ are connected by gears $f f'$, the gear f having one more tooth than f' , in order that J' may have a trifle slower movement than J , and cause the rollers to have a grinding as well as a pressing operation, which is well-calculated to reduce and pulverize the quartz.

Having thus described my invention, what I claim as new, and desire to secure by Letters Patent, is—

1. The toggles C , provided with or connected to the shoes C' , in combination with the slides E , and rubber or other springs F , all arranged to operate in the manner substantially as and for the purpose set forth.
2. The securing of the periphery or shell u of the roller J' to its shaft, g , by means of the India-rubber heads $r r$, expanded by the fixed collars q , loose collars o , and the nuts t , or their equivalents, all arranged substantially as and for the purpose herein set forth.
3. The eccentrics $d d$, applied or arranged in relation with the slides E of the toggles, substantially as and for the purpose specified.

The above specification of my invention signed by me, this eighteenth day of October, 1867.

BENJAMIN BABBITT.
